BRUSH TYPE SWEEPER FOR LITTER AND THE LIKE

Noel W. Fleury, London, England, assignor to Bissell, Inc., Grand Rapids, Mich.

Filed Aug. 5, 1974, Ser. No. 494,768

Term of patent 14 years

Int. Cl. D4—01

U.S. Cl. D4—12

Fig. 1

Fig. 2

Fig. 3

Fig. 4

Fig. 5

Fig. 6

FIG. 1 is a perspective view of a brush type sweeper for litter and the like which embodies my new design;

FIG. 2 is a top plan view thereof;

FIG. 3 is a side elevation of the sweeper, the opposite side being a mirror image thereof;

FIG. 4 is a bottom plan view thereof;

FIG. 5 is a front end elevation thereof; and

FIG. 6 is a rear end elevation thereof.

I claim:

The ornamental design for a brush type sweeper for litter and the like, substantially as shown and described.
